UNITED STATES PATENT OFFICE.

EARL J. EARLY, OF PHILADELPHIA, PENNSYLVANIA.

HOLDER FOR ILLUSTRATED POST-CARDS.

No. 816,904.

Specification of Letters Patent.

Patented April 3, 1906.

Application filed January 24, 1906. Serial No. 297,566.

To all whom it may concern:

Be it known that I, EARL J. EARLY, a citizen of the United States, residing at Philadelphia, in the county of Philadelphia and State 5 of Pennsylvania, have invented certain new and useful Improvements in Holders for Illustrated Post-Cards, of which the following is a specification.

The object of this invention is to form a holder for the storage and display of illustrated postal cards or any similar article which it is desired to carry in stock, so that it can readily be seen and examined and to have the surface of the article as little covered or 10 obstructed as possible. As the holder is formed of wire, the object sought is fully accomplished, the view from either side being equally good, and when the holders are displayed in a window or show-case there need 15 be no turning or other manipulation to see the articles from either side. The holders interlock, so that any desired number may be used, and as they project but slightly they can be used in many places at present unoccupied, and therefore useless, in windows, on 20 columns, walls, and other places where rotatable stands cannot be used. As seen in Figure 3, they may be suspended to swivel or turn in manner to get a good light or for any 25 other convenient purposes. They can be bent to accommodate cards of slightly different lengths.

The invention is illustrated in the accompanying drawings, in which similar parts are 30 designated by similar characters of reference, in which—

Fig. 1 is a front view of a group interlocked and designed to be suspended from a wall, column, a window, or any like situation. 35 Fig. 2 is a back view of a single holder. Fig. 3 is a modification for suspension from a swivel or similar means, so the holders can be turned in different directions.

A single piece of wire of suitable length 40 has at equidistance from its central horizontal part 1 upwardly-bent loops 2 3, which form a means of suspension for the upper member of a series. From the outer side of the loops the holder has downward extensions 4 5 with bends 6 7, from which the wire 45 extends diagonally upward at 8 9 and then runs parallel to parts 4 5 at 10 11 to a distance somewhat below part 1. Parts 10 11 then have outward right-angle bends 12 13 50 parallel to part 1 to a distance to suit the length of the card or object to be held. Then

right-angle inward bends 14 15 are made to limit the projection of the holder and complete the pocket, and parallel to parts 12 13 are the final bends 16 17 in line with parts 1 4 60 5. Parts 16 17 do not reach to members 4 5, leaving spaces 18 19. The upper holder A supports the next holder B, which passes through openings 18 19 and hangs on bends 6 7. Other holders C, D, E, and as many 65 more as are necessary or desirable are suspended in the same way.

Fig. 3 has a loop 20 for the attachment of a swiveling suspension. The angular parts 8 9 form an inclined base whereon the cards or 70 objects rest, as seen at E, each at a different height to enable the withdrawal of one without disturbing the others, which prevents needless handling and soiling.

I claim—

1. A card-holder, or similar article, formed of a single piece of wire bent to have supporting-loops, front and back portions joined by angular bottom portions to support the article or articles stored and displayed, and outward bends at the extremities of the front portions to secure the contained article or articles in endwise position. 75

2. A holder for cards or other articles, formed of a single piece of wire with loops 85 for the support of the upper one, and for the support of succeeding ones, one upon another; front and back portions joined by a bottom part which carries each card at a different elevation; and portions formed to secure the cards in endwise position. 90

3. A series of holders for cards or similar articles, each formed of a single piece of wire, bent and shaped for a central suspension, loops for supporting each one of the series 95 upon another of the series; front and back retaining portions, bottom-retaining portions, and end-retaining portions, with open spaces through which the members of the series may be interlocked or removed from such 100 interlocking.

4. Storage and display holders for cards or like articles, formed of wire, with bends for suspension, front and back parts for confining the objects, bottom parts to support each 105 article at a different elevation, bends at the top of the front members which confine the articles as to their ends, and permit the insertion of another holder to be supported by the holder aforesaid. 110

5. A receptacle for holding and displaying illustrated postal cards or the like, formed

2
and fashioned of wire, in the following manner; first a horizontal back member with loops for suspension, downward extensions therefrom, with bends at their lower ends, 5 from which upwardly extend angular bottom portions on which the displayed objects rest, in different elevations, and from which the wire extends upwardly in practically parallel relation to the back portions and at 10 their upper ends terminate in bends forming three sides of a rectangle to confine the ends of the cards or objects displayed, with openings through which to insert and remove another receptacle to be suspended from the 15 aforesaid receptacle, as and for the purposes set forth.

6. A wire receptacle for the storing and display of goods, fashioned of wire to form sustaining-loops, vertical back portions, front

portions tending diagonally upward from the 20 back portions for a distance then running parallel and terminating in horizontal bends, outward, then backward and lastly inward to near the back portions.

7. A receptacle for the storing and display 25 of post-cards, or like articles, comprising wire bent to vertically pass the back and front of the articles, somewhat remote from their ends, with right-angular loops to confine the 30 articles end-wise and means whereby the receptacles may be interlocked in desired numbers.

In testimony whereof I affix my signature in presence of two witnesses.

EARL J. EARLY.
